LOG LOADER OR THE LIKE

John S. Pilch, Ware, Mass.

Application December 22, 1954, Serial No. 476,929

4 Claims. (Cl. 214—147)

This invention relates to a new and improved tractor mounted log loading apparatus, or the like, and has particular reference to such an apparatus which is relatively simple and inexpensive in construction yet efficient in operation.

Another object is to provide a new and improved log loading apparatus wherein automatic means is provided for clamping logs on the loading apparatus and for releasing the logs therefrom and wherein adjustment of the position of the log supporting means automatically controls the operation of the clamping means.

Another object of the invention is to provide an apparatus of the type set forth wherein the same hydraulic means as is employed for actuating the platform or support automatically and simultaneously actuates the upper tong or clamping member.

Other objects and advantages of the invention will be apparent from the following description taken in connection with the accompanying drawings. It will be understood that changes may be made in the details of construction and arrangement of parts shown and described without departing from the spirit of the invention as set forth in the accompanying claims as the preferred form has been given by way of illustration only.

Referring to the drawings:

Fig. 1 is a side view of a tractor mounted platform which can be employed in constructing the loading apparatus of the invention;

Fig. 2 is a view similar to Fig. 1 but showing the log loading apparatus of the invention;

Fig. 3 is a fragmentary view similar to Fig. 2 but illustrating the operation of the invention;

Fig. 4 is a fragmentary view generally similar to Fig. 3 but illustrating another step in the operation of the device;

Fig. 5 is a view taken on line 5—5 of Fig. 2 looking in the direction of the arrows; and

Fig. 6 is a view taken on line 6—6 of Fig. 2 looking in the direction of the arrows.

Referring more particularly to the drawings wherein similar reference characters designate corresponding parts throughout, there is shown in Fig. 1 a tractor mounted platform or fork which can be utilized in forming the log loading apparatus of the present invention.

In Fig. 1 there is shown the tractor having the engine 1, seat 2 for the operator and tracks 3. Adjacent the opposite sides of the tractor are the spaced supports 4 to which is secured the control valve 5 for the hydraulic system and which valve is adapted to be controlled by the operator by controlling operating levers 6.

The control valve 5 is adapted to receive fluid under pressure from hydraulic pump 7 through lines 8 and 9.

Pivottally connected to each of the upright supports 4 is an arm 10 and to the forward or outer ends of the arms 10 are pivottally connected the lugs 10a on the platform which consists of the spaced upright supports 11 and the supporting platform or fork 12.

The lugs 10a are pivottally connected to the forward ends of arms 10 at 13. The arms 10 are adapted to be

2

raised or lowered by means of cylinders 28 and rams 29 which are pivottally connected to the supports 4 at 30 and to the arms 10 at 31.

The platform is adapted to be pivoted about arms 10 by means of cylinders 14 and rams 15. Cylinder 14 is pivottally connected at 14a to upright supports 4 above the pivotal connection of arms 10 and rams 15 are pivottally connected at 15a to links 32 which in turn are pivottally connected at 33 to lugs 34 on the uprights 11.

10 The links 32 are connected to arms 10 by means of spaced links 35 and 36 which are pivottally connected at one end to links 32 and at their opposite ends to lugs 37 on the lower side of arms 10.

15 In the log loading apparatus of the present invention the cylinders 14 are pivottally connected at 16 to lugs 16a on the upper side of arms 10 and rams 15 are pivottally connected at 27 to links 38 which are pivottally connected at 39 to lugs 34 and link 26 is also pivottally connected to link 38 at 27 and to lugs 37 at 28.

20 The forward ends of arms 10 are connected by the cross member 40.

In forming the log loading device of the present invention, the support 20 is provided between the arms 10 with its ends 20a secured on pivots 13 and said ends 20a have the projecting lugs 20b which are positioned beneath member 40 for locking member 20 in fixed relation to arms 10.

25 The tong or clamping member 17 is pivottally connected to member 20 at pivot 21 and is adapted to extend outwardly over fork 12 and to cooperate with fork 12 by clamping logs, or the like, on the fork or releasing such clamping action depending upon the pivotal movement of the fork.

30 For effecting such movement of tong or clamp 17 there is provided a link 18 which is pivottally connected at 24 to a lug 24a on the support 11 and link 18 is pivottally connected to tong 17 at 19. It will be noted that a plurality of pivot points 19a may be provided, either of which may be employed for pivotal connection 19 and

35 which are adapted to adjust the position of tong 17.

35 It will be seen that with the support 20 in fixed relation to arms 10 and with the tong 17 pivottally connected thereto and with link 18 pivottally connected at one end to tong 17 and its opposite end to tong 24a, that movement of fork 12 in a downward direction for unloading, as shown in Fig. 4, will automatically pivot tong 17 away from the fork and the logs thereon and thereby automatically release the clamping action of the tongs 17 on the logs.

40 It will be seen from Fig. 3 that movement of fork 12 in a direction toward tong 17 will, because of the movement of lug 24a in the opposite direction, automatically effect pivotal movement of tong 17 about pivot 21 toward logs A and fork 12 whereby said tong is moved into 45 clamping engagement with the logs A on fork 12.

45 In operation, the apparatus is set in the position shown in Fig. 2, namely, with the fork 12 on the ground and the device is then moved toward the logs A whereby the fork 12 will be pushed beneath the logs. By actuating cylinder 14 and ram 15, the fork 12 is then pivoted upward as shown in Fig. 3, which automatically pivots tong 17 into clamping engagement with the logs A to retain the logs on the fork 12. By cylinder 28 and ram 29 the arms are then raised which raises the logs from the ground

50 and then by movement of the tractor the logs can be moved to loading position at which time the pivoting of fork 12 by cylinder 14 and ram 15 to unloading position, as shown in Fig. 4, effects automatic disengagement of tong 17 from the logs and with the fork inclined downwardly, as shown in Fig. 4, the logs will, when released by 55 the tong 17, drop from the fork 12.

55 From the foregoing it will be seen that I have provided

new and improved means for obtaining all of the objects and advantages of the invention.

I claim:

1. In a device of the character described, a pair of push arms adapted to be pivotally connected to a tractor, a platform pivotally connected to said push arms adjacent the free ends thereof, hydraulic means for pivoting said platform relative to said push arms, said platform comprising a forwardly extending fork and an upright support rigidly connected to said fork, a clamping member for retaining material on said platform, a link pivotally connected to said platform and to said clamping member, and a spanning support pivotally connected adjacent its ends to said push arms and connected intermediate its ends to said clamping member whereby pivoting of said platform upwardly for loading will urge said clamping member toward said platform and pivoting of said platform downwardly for unloading will pivot said clamping member upwardly.

2. In a device of the character described, a pair of push arms adapted to be pivotally connected to a tractor, a platform pivotally connected to said push arms adjacent the free ends thereof, hydraulic means for pivoting said platform relative to said push arms, said platform comprising a forwardly extending fork and an upright support rigidly connected to said fork, a clamping member for retaining material on said platform, a link pivotally connected to said platform and to said clamping member, and a substantially inverted U shaped spanning support pivotally connected adjacent its ends to said push arms and connected intermediate its ends to said clamping member whereby pivoting of said platform upwardly for loading will urge said clamping member toward said platform and pivoting of said platform downwardly for unloading will pivot said clamping member upwardly.

3. In a device of the character described, a pair of push arms adapted to be pivotally connected to a tractor, a platform pivotally connected to said push arms adjacent the free ends thereof, hydraulic means for pivoting said platform relative to said push arms, a link connect-

ing said hydraulic means and said platform, said platform comprising a forwardly extending fork and an upright support rigidly connected to said fork, a clamping member for retaining material on said platform, a link pivotally connected to said platform and to said clamping member, and a spanning support pivotally connected adjacent its ends to said push arms and connected intermediate its ends to said clamping member whereby pivoting of said platform upwardly for loading will urge said clamping member toward said platform and pivoting of said platform downwardly for unloading will pivot said clamping member upwardly.

4. In a device of the character described, a pair of push arms adapted to be pivotally connected to a tractor, 15 a platform pivotally connected to said push arms adjacent the free ends thereof, hydraulic means for pivoting said platform relative to said push arms, a link connecting said hydraulic means and said platform and a pivotable lever pivotally connected adjacent its opposite ends to said link connecting the hydraulic means and the platform and to said push arms, said platform comprising a forwardly extending fork and an upright support rigidly connected to said fork, a clamping member for retaining material on said platform, a link pivotally 20 connected to said platform and to said clamping member, and a spanning support pivotally connected adjacent its ends to said push arms and connected intermediate its ends to said clamping member whereby pivoting of said platform upwardly for loading will urge said clamping member toward said platform and pivoting of said platform downwardly for unloading will pivot said clamping member upwardly.
